United States Patent Office

Des. 186,988
Patented Jan. 5, 1960

186,988

COASTER

Nelda A. Miller, Kansas City, Mo.

Application August 13, 1959, Serial No. 57,170

Term of patent 14 years

(Cl. D44—10)

Fig. 1.

Fig. 2.

Fig. 3.

Fig. 4.

Fig. 1 is a perspective view of a coaster embodying my new design;

Fig. 2 is a plan view of same;

Fig. 3 is a side elevational view of same; and

Fig. 4 is a cross-sectional view of same, taken along the line 4—4 of Fig. 2 in the direction of the arrows.

I claim:

The ornamental design for a coaster, as shown.
